UNITED STATES PATENT OFFICE.

BERNARD C. GROH, OF ST. PAUL, MINNESOTA, ASSIGNOR TO AUTOMATIC ELECTRIC COMPANY, OF CHICAGO, ILLINOIS, A CORPORATION OF ILLINOIS.

TELEPHONE REPEATER.

1,416,663.

Specification of Letters Patent. Patented May 16, 1922.

Application filed March 18, 1916. Serial No. 83,838.

To all whom it may concern:

Be it known that I, BERNARD C. GROH, a citizen of the United States of America, and resident of St. Paul, Ramsey County, Minnesota, have invented a certain new and useful Improvement in Telephone Repeaters, of which the following is a specification.

My invention relates to an improved impulse repeater for automatic or semi-automatic telephone systems, and it relates more specifically to a repeater adapted for use in a common battery telephone system in which the automatic switches are controlled over two sides of the line in series.

An object of my invention is to provide a repeater in which positive and efficient transmission of electrical impulses is secured and in which all bridges are removed from across the talking circuit upon the response of the called substation.

A further object of my invention is the provision of a repeater to operate on trunk lines where the length of the trunk line is such that it is not satisfactory to send the original impulses over the entire distance to control and operate automatic switches and in which the transmission of voice currents is greatly facilitated because of the removal of bridges from across the trunk line.

To the foregoing and other useful ends my invention consists of matters hereinafter set forth and claimed.

In the accompanying drawings Fig. 1 represents a general layout of the system, in which I have chosen to illustrate my invention. Referring to Fig. 1 it is assumed that the automatic substation A, whose line terminates in the exchange X, desires connection with the automatic substation A', whose line terminates in apparatus at exchange Z. It is further assumed that the exchanges X and Z are at such a distance apart that satisfactory operation, in setting up a connection, is not obtained. By the addition of my improved repeater, on the trunk line at exchange Y, which is between exchanges X and Z, highly efficient results are secured, both as regards the transmission of electrical impulses and of voice currents.

Figs. 2, 3 and 4 taken together represent a complete connection between a calling

substation A and a called substation A' embodying the principles of my invention.

Figs. 5 and 6 illustrate the operating and talking circuits of the repeater R.

The system herein illustrated is of a well known type, known as a two-wire system, and is equipped with individual or line switches C divided into groups, each group controlled by a master switch D. There are also provided the group selectors E and E', repeaters F and R and connectors H. The current for operating and talking purposes being supplied by the batteries B, B', and B². The subscriber's station A is connected with the central office through the line conductors 1 and 2, which terminate in a line switch C, said switch being one of a group of switches governed by the master switch D.

By means of the line switch C the line is extended to the selector E. The selector E selects the repeaters F and R which control the selector E' at exchange Z. Selector E' extends the connection to the connector H which completes the connection to called subscriber's telephone A'.

The telephone at the substation A is provided with a receiver 3, transmitter 4, ringer 5 and condenser 6. It is also provided with a suitable impulse-sending device similar to that shown and described in United States Letters Patent to J. G. Blessing, No. 1,119,394, granted December 1, 1914, and comprises an impulse-wheel 7, springs 8 and a dial (not shown) which has holes around its periphery for convenience in rotating. The dial controls the impulse-wheel to open and close the impulse springs 8 a number of times corresponding to the digits of the called number.

The line switch C and the master switch D are of the general type of line and master switches disclosed in British patent to R. W. James, No. 26,301 of 1906 and of the type shewn in British patent to T. G. Martin, No. 1419 of 1910, being however, more particularly of the form shown in United States Letters Patent to F. Newforth, Jr., No. 13,901, re-issued April 13, 1915. As herein represented, the line switch C comprises among other details, a plunger (not shown) which is attached to the end of a plunger arm 9, that is controlled by the magnet 10.

The magnet 10 comprises a pull-in winding 11 and a holding or cut-off winding 12. The pull-in winding 11 is only strong enough to operate the cut-off armature 13 but is strong enough to hold the plunger arm 9 in its operated position after it has been operated by the pull-in winding. The line relay 14 controls the circuit of the pull-in winding 11. When the plunger arm is attracted by the magnet 10 the plunger is thrust into a group of bank springs 15, 16, 17, 18, 19, 20, 21, and 22, forcing them into contact in pairs. Although only one set of springs, 15 to 22, is shown, each switch is provided with a plurality of such sets, each set forming a terminal of a separate trunk line leading to a selector such as E. These sets of trunk line terminals are, of course, multiplied to the corresponding sets in the banks of the other line switches in the same group. The plungers of all the line switches of the group which are controlled by the master switch D engage a plunger shaft, through the medium of which said master switch normally maintains the plungers opposite the terminals of an idle trunk line.

The selector E is of the general type of selector switch disclosed in United States Letters Patent No. 815,321, granted to Keith, Erickson and Erickson, March 13, 1906, the side-switch being dispensed with and the circuits modified in order to adapt the switch for operation in a system in which the central office apparatus is controlled by impulses delivered over two sides of the line in series. Among other details the selector comprises the line relay 23, release relay 24, vertical magnet 25, rotary magnet 26 for moving the switch shaft to which is attached the wipers 27, 28 and 29. There is also provided the switching relay 30, controlling relays 31 and 32, and the release magnet 33. The springs 34 and 35 are closed when the switch shaft moves one step from its lowest or normal position.

The repeater F comprises a line relay 36, slow relays 37 and 38, battery reversing relay 39, impedance coil 40 and condensers C¹ and C². The line relay 36 is bridged across the trunk line extending from the selector E to the repeater, and is arranged so that, when its armature operates in accordance with the impulses from the subscriber's station A, it opens and closes the bridge across the trunk extending to the repeater R, a corresponding number of times. Among the functions of this repeater is to receive the electrical impulses from the subscriber's impulse sender and repeat them to the repeater R which is further along the trunk. Furthermore, it supplies battery current to the calling line for talking purposes and maintains a holding circuit for the switches C and E.

The trunk line conductors 41 and 42 ex-

tend from the repeater F to the repeater R. The repeater R has a line relay 43, slow relays 44 and 45, slow-acting controlling relay 46, polarized relay 47, resistance coil 48 and condensers C³ and C⁴.

The repeater R is connected to the selector E' by means of the trunk line conductors 49 and 50. The selector E' is similar to the selector E and comprises a line relay 51, release relay 52, vertical magnet 53, rotary magnet 54, switching relay 55, controlling relay 56, slow relay 57 and release magnet 58. The switch shaft (not shown) carrying the wipers 59, 60 and 61, has a vertical and rotary movement controlled by the magnets 53 and 54. The switch shaft, when in its lowest position, separates the springs 62 and 63 and allows them to engage upon its first step. The selector extends the connection to the connector H which latter is of the type disclosed in United States Letters Patent No. 815,176 granted March 13, 1906 to Keith, Erickson & Erickson, but is modified to adapt it for use in a two wire system. Among other details the connector comprises a line relay 64, release relay 65, vertical magnet 66, rotary magnet 67, private magnet 68, back bridge relay 69, ringer relay 70, private control relay 71, and ringer cut-off relay 72. This switch has the usual shaft, carrying the wipers 73, 74 and 75, having vertical and rotary movement controlled by the vertical and rotary magnets.

The line switch C¹ and the substation A' are the same as line switch C and substation A.

Having given a general description of the apparatus involved in the system and as the line switch, selector, connector and repeater F herein shown, are well known to those versed in the art, their operation will be described in a more or less general manner. I will now describe how a subscriber at substation A may obtain connection with a subscriber at substation A', the number of which we will assume to be 2220.

Upon the removal of the receiver 3 from the switch hook the line switch C is tripped in the well known manner, so as to thrust its plunger into the terminal bank thereby forcing springs 15, 17, 19 and 21 into contact with springs 16, 18, 20 and 22, respectively. The calling line is thus placed into connection with the selector switch E, energizing the line relay 23, which pulls up and closes a circuit to release relay 24. Release relay 24, upon energizing, supplies a holding ground G³ through springs 76, springs 18 and 17, thence over two paths, one leading through the hold-in winding 12 to the battery B, the other of which leads to the private normal conductor 77 to the private contacts of the connectors adapted to seize the line of substation A. Upon the operation of the calling device for the first digit, the 130

circuit of the line relay 23 is momentarily opened twice at the impulse springs 8, thereby deenergizing said line relay a corresponding number of times to cause the selector to 5 be stepped up two steps, in the well-known manner, opposite the second row of contacts in which terminate the trunk lines leading to the repeater F, whereupon the magnet 26 operates in the usual manner to rotate the 10 shaft wipers onto an idle trunk line whereupon the switching relay 30 energizes to extend the line connection to the line relay 36 of repeater F.

The line relay 36, upon energizing, closes 15 a circuit to the slow-acting relay 37 which extends from ground G⁴ through springs 78 and 79 and the relay 37 to the battery B. The relay 37, upon energizing, supplies a holding ground for the selector E and line 20 switch C to relieve the ground G³ which is removed when the switching relay 30 opens the circuit to relays 23 and 24. The holding ground is furnished over a circuit that extends from ground G⁵ through springs 80 25 to a point 81, wiper 28, to a point 82, thence over two paths, one of which extends through springs 83 and the switching relay 30 to battery, the other path extends from the point 82, springs 35 and 84, springs 18 30 and 17, and the holding winding 12 to battery B. Another circuit is closed at this time extending from ground G⁵ through springs 80, point 81, right-hand winding of relay 39 to the battery B. A further result 35 of the energization of relay 37 is the closure of springs 85, thereby preparing a circuit for the slow relay 38. Another result of the energization of line relay 36 is the closure of springs 86 thereby closing a circuit for 40 line relay 43 of repeater R which extends from ground G⁶ through lower winding of relay 43, springs 87 and 88, conductor 42, springs 86, impedance coil 40, left-hand winding of relay 39, return conductor 41, 45 springs 89 and 90, upper winding of relay 43 to the battery B'. Both windings of relay 39 now carry current which is in the direction to oppose each other and the armature remains unoperated. The line relay 43 energizes over the above circuit and 50 closes a circuit to slow acting relay 44 extending from ground G⁷ through springs 91 and 92 and the said relay 44 to the battery B'. Relay 44, upon energizing, prepares, at its springs 93, a circuit for slow 55 relay 45. A further result of the energization of line relay 43 is closure of a circuit to the selector E' extending from ground G⁸ through the lower winding of line relay 60 51, springs 94, conductor 50, springs 96, lower winding of relay 47, springs 97 and 98, upper winding of relay 47, springs 99 and 100 of relay 45, return conductor 49, springs 95 and the upper winding of line 65 relay 51 to the battery B². The relay 47 is a magnetically-polarized relay, and attracts its armature in one direction when it receives current of one polarity and in the other direction when it receives current of opposite polarity. The springs 101 of said relay 47 70 are normally separated and it receives current at this time to maintain them separated. The line relay 51 of selector E' energizes over the above circuit and closes a circuit for the release relay 52.

75

The central office apparatus is now in condition to receive the second digit of the called number, whereupon the calling device is operated in the usual manner, opening the circuit of the line relay 36 of the repeater 80 F, twice momentarily. The slow-acting relay 37 retains its armature in the operated position during the momentary interruptions of its circuit by relay 36 responding to the impulses. Therefore, the ground G⁵ 85 is held upon the release trunk, thus holding up the preceding switches. Each time that the line relay armature drops back, a circuit is completed from ground G⁴ through springs 78 and 102 springs 85 and slow relay 38 to the battery B. The result is that the first time the circuit is broken for the second digit, relay 38 closes a direct bridge across the trunk, and since said relay 38 is slow-acting this bridge is maintained closed 90 at springs 103 and 104 during the subsequent impulses of the digit. Each time the armature of line relay 36 drops back in responding to the momentary interruptions of the calling device, it opens this bridge at springs 100 95 86 and thus repeats impulses to the repeater R. It is well to note that impedance coil 40 and left-hand winding of relay 39 are short-circuited by springs 103 and 104 during the transmission of impulses. The right-hand 105 winding of said relay 39 continues to carry current but is of insufficient strength to pull up the armature.

The line relay 43 of repeater R responds to the momentary interruptions of its circuit. 110 The slow-acting relay 44 retains its armature in the operated position during the transmission of impulses. Therefore the first time the armature of line relay 43 drops back in responding to the impulses, a circuit 115 is completed which extends from ground G⁷ through springs 91 and 105, springs 93 and the relay 45 to battery B'. The relay 45, upon energizing, closes a direct bridge across the trunk line conductors 49 and 50 at 120 springs 100 and 106 which includes springs 96 of the line relay 43. Since said relay 45 is slow-acting, it maintains said bridge closed during the subsequent impulses. The line relay 43 in responding to the impulses 125 transmitted from repeater F, opens the bridge at springs 96 to repeat impulses to the selector switch E'. The selector line relay 51 is thus operated to transmit impulses to the vertical magnet 53 to thereby step the 130

4
 shaft wipers to the second level of back contacts leading to connectors such as H. The selector stops upon the first idle contact, in the well known manner, whereupon the 5 switching relay 55 operates to switch the line circuit through to the connector H, to energize the line relay 64. The line relay 64, upon energizing, closes a circuit for release relay 65, which, upon energizing, 10 applies a holding ground upon the release conductor to selector E' which extends from ground G⁹ through springs 107, release conductor 108, wiper 60, springs 109 of relay 56 and the relay 55 to the battery B². The 15 selector E' is thus held in its operated position. Another result of the energization of relay 65 is the opening of the circuit of the release magnet 110 by disengaging springs 111 and 112 and the preparation of 20 the vertical magnet circuit by the closing of springs 111 and 113.

The calling device may now be operated for the third digit 2, deenergizing the line relay 36 of repeater F, twice, which deenergizes line relay 43 of repeater R, twice, which in turn deenergizes the line relay 64 of the connector twice. The armature of said line relay 64 upon falling back transmits two impulses to the vertical magnet 30 over a circuit which extends from ground G¹⁰ through springs 114 and 115, springs 111 and 113, relay 71, vertical magnet 66, side-switch wiper 116 to the battery B². The vertical magnet receives two impulses 35 over this circuit and operates to raise the switch shaft and wipers two steps to a position opposite the second level of bank contacts in which are situated the terminals of the called subscriber's line. The slow controlling relay 71 is energized by the first 40 impulse and maintains its armature in its operated position during the subsequent impulses of the digit. In its energized position the relay 71 closes an energizing circuit 45 for the private magnet 68. The pause, after the impulses have been delivered, permits the controlling relay to deenergize which allows the private magnet to fall back and causes the side switch to pass to second position. 50 The side switch wiper 116 upon passing to second position transfers the battery connection from the vertical magnet 66 to the rotary magnet 67. The subscriber now operates his calling device for the last digit 55 0, thus sending in ten impulses and thereby operating the line relay 64 of the connector in the same manner as previously described. The relay 64 operates a corresponding number of times to close a circuit through the 60 rotary magnet 67, rotating the line and private wipers ten steps onto the contacts of the desired line. The relay 71 and private magnet 68 operate in the same manner as for the preceding digit. The private mag- 65 net upon deenergizing permits the side

switch to pass from second to third position. When the side switch wiper 117 passes to third position an energizing circuit is established for the cut-off winding 118 of the called subscriber's line switch which extends 70 from ground G¹¹ through side switch wiper 117 (in third position), private wiper 74 and the cut-off winding 118 to battery B². The side switch wipers 119 and 120, upon passing to their third position contact points, 75 complete the line circuit to the called line. Side switch wiper 116, upon engaging its third position contact, closes a circuit that extends from ground G¹² through interrupter 121, ringing relay 70, springs 122 80 and side switch wiper 116 to the battery B². The ringer relay 70 is energized intermittently over the above circuit and operates to separate the called line from the calling line and to bridge the ringing current generator RG across the called line to signal the called subscriber. Upon the subscriber at substation A' removing his receiver to answer the call, and as soon thereafter as the ringing relay deenergizes if it happens 90 to be energized at the time, a circuit to the back bridge relay 69 is closed at substation springs 123. Said circuit being traced from ground G¹³ through the left hand winding of relay 69, springs 123 of private magnet 95 68, over heavy conductor through contact springs of ringing relay 70, wiper 75, to and through the called substation back over wiper 73, another pair of contact springs of ringing relay 70, springs 124 of private 100 magnet 68 and the right-hand winding of back bridge relay 69 to the battery B². Talking current is supplied over the above traced circuit to the called subscriber. Upon the energization of said back-bridge relay 105 69, a circuit is closed from ground G¹¹ through side switch wiper 117, springs 125 and relay 72 to battery B². Relay 72, upon energizing, opens the circuit of ringing relay 70 at springs 122, and at springs 126 110 closes a locking circuit for itself which extends from ground G¹¹ through side switch wiper 117, springs 126 and the relay 72 to the battery B². A further result of the energization of back bridge relay 69 is the 115 reversal of the direction of current flow in the direction of the calling subscriber. This reversal of current, of course, flows through polarized relay 47 and is in the opposite direction to the previous current, thereby 120 causing said relay to pull over its armature in the direction to close the contacts at 101. A circuit is then closed from ground at G¹⁴ through contacts 101, relay 46 to the battery B'. The relay 46, upon energizing, places 125 the line relay 43 in another or local circuit to maintain it energized. This circuit for relay 43 extends from ground G⁶ through springs 87 and 127, resistance 48, and the upper winding of relay 43 to the battery 130

B'. A further result of the energization of relay 46 is the shifting of springs 89, 97 and 87 out of engagement with springs 90, 98 and 88 and into engagement with springs 128, 129 and 127, whereby the upper winding of relay 47 is bridged across the condenser C³ and the lower winding is bridged across the condenser C⁴.

The energizing circuit for the connector line relay 64 now extends from ground through the lower winding of said line relay, through springs 135 and 136, line wiper 59, springs of relay 55 of selector E', conductor 49, springs 100 and 99 of relay 45, upper winding of relay 47, springs 128 and 89 of relay 46, conductor 41, left-hand winding of relay 39, impedance coil 40, springs 86, return conductor 42, springs 129 and 97 of relay 46, lower winding of relay 47, springs 96 of relay 43, return conductor 50, springs of relay 55, line wiper 61, springs 137 and 138 of relay 69 and the upper winding of line relay 64 to the battery B². The circuit shown in Fig. 5 illustrates the condition of repeater R before the called party removes his receiver. The circuit illustrated in Fig. 6 shows the condition of repeater R after the called party answers. The relay 46 is preferably made slow-acting so that if the calling subscriber operates the calling device after the called subscriber has answered, the relay 46 will not respond to the momentary interruptions of its circuit caused by the operation of relay 47. It is thus seen that the repeater R is free of bridges after the called party answers. The reversed battery as traced from the connector is supplied through the windings of relay 47 along the trunk conductors 41 and 42 through the left-hand winding of relay 39 in series with impedance coil 40. The two windings of relay 39 will now carry current in the same direction, whereby the armature of said relay is attracted, which reverses the direction of flow of battery current in the calling subscriber's line. The subscribers may now converse and after the conversation is finished the connection is released by the calling subscriber hanging up his receiver, thereby breaking the line circuit at springs 130, at substation A. The opening of the line circuit at substation A, opens the circuit of the line relay 36 of repeater F. Upon relay 36 deenergizing, the circuit of slow acting relay 37 is opened, thus removing the holding ground G⁵ from the switching relay 30 of selector E as well as from the holding winding 12 of the line switch C. Upon switching relay 30 falling back a circuit is closed to the release magnet 33 which extends from ground G¹⁵ through springs 131, springs 132, springs 133, springs 34 and the release magnet 33 to the battery B. The release magnet 33, upon energizing, restores the switch shaft and wipers to their normal position, and its own circuit is opened at springs

34 when the shaft reaches its normal position. The holding winding 12 of the line switch, upon deenergizing, permits the plunger-arm 9 to withdraw the plunger from the bank of contacts and also allows the cut-off arm 13 to be released to once more bridge the line relay 14 across the line.

The deenergization of line relay 36 of repeater F, by the separation of springs 86 opens the circuit of line relay 43, assuming the called subscriber restores his receiver to its switchhook ahead of the calling subscriber. Relay 43, upon deenergizing, opens the circuit of relay 44 and at springs 96 opens the energizing circuit of line relay 64 of connector H. Relay 64, upon deenergizing breaks the circuit of release relay 65 which removes the holding ground G⁶ from the switching relay 55 of selector E'. The selector E' releasing in the same manner as was described in connection with selector E. A further result of the deenergization of relay 65 is the closure of a circuit extending from ground G¹⁰ through springs 114 and 115, springs 111 and 112, springs 134 and 135, and the release magnet 110 to the battery B². The release magnet, upon energizing, restores the shaft and side-switchwipers to their normal position and its own circuit is opened at springs 134 when the shaft reaches its lowest or normal position. The circuit of cut-off winding 118 of switch C¹ is broken when the connector releases thereby placing the line relay of the line switch across the line. If, however, the calling subscriber places his receiver upon the switchhook ahead of the called subscriber, then the release of the connector is controlled direct from the repeater F instead of by the repeater R. In that event when the line relay 36 of repeater F separates springs 86, the energizing circuit including relay 47 of repeater R and line relay 64 of the connector is broken. The relay 47, upon deenergizing, opens the contact of springs 101, thereby de-energizing relay 46. Relay 46, upon deenergizing, places the line relay again across the trunk, the circuit of which is now broken, which causes said relay 43 to deenergize. Upon the relay 43 deenergizing, the circuit for relay 44 is opened and the repeater relays are placed in their normal condition. The connector H controls the release of the selector E' and releases itself in the same manner as hereinbefore described.

Assuming that the called line is busy there will then be a guarding ground potential upon the connector private bank contact. The connector H upon attempting to complete a connection with the busy line, will maintain its side switch wipers in the second position thus preventing completion of the connection. As soon as the relay 71 deenergizes after the last digit of impulses have been delivered and while side switch is in

second position a circuit is closed from ground upon the connector private bank contact, through private wiper 74, side switch wiper 117 (in second position), 5 springs 139 and 140, busy relay 141, springs 142, private magnet 68 to the battery B². The busy relay 141, upon energizing, forms a locking circuit for itself extending from ground G¹⁶ through springs 143, springs 10 144 and 140 of relay 141, the said relay 141, springs 142 and the private magnet 68 to the battery B². A further result of the energization of the busy relay is the opening of the rotary magnet circuit at springs 15 146 and the closing of springs 145, whereby a busy tone from the busy machine Q is furnished to the calling subscriber by way if side switch wiper 120, conductor 50, conductor 42, line conductor 1, to and through 20 the subscriber's substation, return conductor 2 to the negative pole of battery, whereupon the receiver is replaced on the switch hook and the connection is released in practically the same manner as previously described.

25 In connection with the repeater R it is seen that as soon as the called subscriber removes his receiver from its switchhook in answering the call, the relation of windings of relay 47 with respect to the trunk is altered. Before the called party answers the relay 47 is bridged across the called side of the repeater as shown in Fig. 5. After the called party answers the front bridge relay 43 is removed from the trunk and placed in a 30 local circuit, while the windings of relay 47 are placed in multiple with the condensers C³ and C⁴ as shown in Fig. 6. It is thus seen that all bridges are eliminated from the repeater R during talking and the transmission of voice-currents is greatly facilitated.

35 It is thus evident that I have devised a very efficient form of repeater for transmitting electrical impulses during the setting up of the connection and one in which all 40 bridges or bypasses for voice currents are removed during the talking stage of the operations.

45 While I have illustrated my invention in connection with a full automatic telephone system of a particular type, it will be readily apparent that my repeater is equally as well adapted for use in other types of automatic systems, or with semi-automatic telephone systems. Various modifications and changes 50 in the repeater itself will likewise be suggested to those skilled in the art and come within the broader aspects of my invention.

55 What I claim as my invention is:

1. In a telephone system, a calling and a 60 called line, means including a plurality of automatic switching mechanisms for connecting said lines, a relay for controlling the progressive motion of one of said mechanisms to extend a connection to another one 65 of said mechanisms and for then controlling

said other mechanism over said extension, said relay normally connected in bridge of the line conductors at one of said mechanisms, said bridge including a battery and said relay in series, and a relay actuated 70 upon the closure of the called line circuit for causing the disconnection of said controlling relay from in bridge of the line, said bridge so connected normally that there is no flow of current through any part 75 thereof.

2. In a telephone system, a calling and a called line, means including a repeater and automatic progressively movable switches controlled thereby for connecting said lines 80 in a metallic talking circuit, a line relay for controlling the progressive motion of one of said switches to extend a connection to another one of said switches and for then controlling said other switch over said extension, said relay normally in bridge of the line conductors at said repeater, said bridge including a battery and said relay in series, and means for automatically opening said bridge during conversation, said bridge so 85 connected normally that there is no flow of current through any part thereof.

3. In a telephone system, a calling and a called line, means including a repeater and automatic progressively movable switches 90 controlled thereby for connecting said lines in a metallic talking circuit, a line relay for controlling the progressive motion of one of said switches to extend a connection to another one of said switches and for then controlling 95 said other switch over said extension, said relay normally in bridge of the line conductors at said repeater, said bridge including a battery and said relay in series, and means controlled by the response of the called subscriber for 100 disconnecting said relay from in bridge of the line, said bridge so connected normally that there is no flow of current through any part thereof.

4. In a telephone system, a calling and a 110 called line, means including a repeater and automatic progressively movable switches controlled thereby for connecting said lines in a metallic talking circuit, a line relay for controlling the progressive motion of one 115 of said switches to extend a connection to another one of said switches and for then controlling said other switch over said extension, said relay normally in bridge of the line conductors at said repeater, said bridge including a battery and said relay in series, a second relay in said repeater for opening 120 said bridge during conversation, and means for controlling said second relay from said switch over the line conductors extending 125 between the said switch and repeater, said bridge so connected normally that there is no flow of current through any part thereof.

5. In a telephone system, a temporarily 130 established connection between a calling and

a called line including a repeater, a line relay in said repeater controlling the maintenance of the connection, said line relay being normally included in a bridge of the 5 line conductors at said repeater but temporarily disconnected therefrom, and a local circuit for maintaining said line relay energized during conversation.

6. In a telephone system, means for connecting a calling and a called line including 10 a repeater and an automatic switch, means for closing a bridge across the line conductors at said repeater to prevent the release of said switch after the same has been 15 operated, and means for opening said bridge during conversation and for closing the same over a different path.

7. In a telephone system, means for connecting a calling and a called line including 20 a repeater and an automatic switch, means for closing a bridge across the line conductors at said repeater to prevent the release of said switch after the same has been operated, inductive windings in said bridge, 25 means for opening said bridge and for connecting said windings serially in the line circuit, and a second bridge across the line at another point for preventing the release of said switch during conversation.

30 8. In a telephone system, means for connecting a calling and a called line including a repeater and an automatic switch, means for closing a bridge across the line conductors at said repeater to prevent the release 35 of said switch after the same has been operated, means for automatically opening said bridge when the called subscriber answers, and additional means for preventing the release of said switch during conversation.

40 9. In a telephone system, means for connecting a calling and a called line including a trunk line comprising two inductively connected sections, a repeater at the junction of said sections, a double wound controlling 45 relay connected in a bridge of one section of the trunk line, and means for conductively uniting the conductors of said sections by way of the windings of said relay.

50 10. In a telephone system, means for connecting a calling and a called line including a trunk line comprising two inductively connected sections, a repeater at the junction of said sections, a double wound controlling relay connected in a bridge of one section of 55 the trunk line, and means controlled by the subscriber on the called line for conductively uniting the conductors of said sections by way of the windings of said relay during conversation.

60 11. In a telephone system, means for connecting a calling and a called line including a trunk line comprising two inductively connected sections, a repeater at the junction of said sections, a double wound controlling 65 relay connected in a bridge of one section of

the trunk line, and circuit controlling mechanism for changing said relay in relation to said trunk line from bridged to series connection.

12. In a telephone system, a trunk line 70 comprising two inductively connected sections, the second section terminating in an automatic progressively movable switch, a relay in bridge of the first section and energized over the conductors thereof to close a 75 control circuit over said second section for causing the progressive motion of said switch, means for operating said switch through the medium of said relay and control circuit to establish a talking circuit between a calling and called line, and means for automatically disconnecting said relay from in bridge of said trunk line during conversation, said bridge so connected normally 80 that there is no flow of current through any 85 part thereof until the conductors of said first section are connected together.

13. In a telephone system, a trunk line comprising two inductively connected sections, the second section terminating in an 90 automatic progressively movable switch, a relay in bridge of the first section and energized over the conductors thereof to close a control circuit over said second section for causing the progressive motion of said 95 switch, means for operating said switch through the medium of said relay and control circuit to establish a talking circuit between a calling and called line, means for automatically disconnecting said relay from 100 in bridge of said trunk line during conversation, and for maintaining the same energized over a local circuit to prevent the release of the connection, said bridge so connected normally 105 that there is no flow of current through any part thereof until the conductors of said first section are connected together.

14. In a telephone system, a trunk line comprising two inductively connected sections, the second section terminating in an 110 automatic switch, a relay in bridge of the first section and energized over the conductors thereof to close a control circuit for said switch, means for operating said switch through the medium of said relay and control circuit to establish a talking circuit between a calling and called line, an inductive winding in said control circuit constituting a bridge of said second section, and automatic means for holding said second bridge 115 open during conversation.

15. In a telephone system, a trunk line comprising two inductively connected sections, the second section terminating in an 120 automatic switch, a relay in bridge of the first section and energized over the conductors thereof to close a control circuit for said switch, means for operating said switch through the medium of said relay and control circuit to establish a talking circuit be- 125 130

5 between a calling and called line, an inductive winding in said control circuit constituting a bridge of said second section, and automatic means for holding both bridges open during conversation.

16. In a telephone system, a trunk line comprising two inductively connected sections the second of which terminates in an automatic switch, a repeater at the junction 10 of said sections, a line relay in bridge of the first section at said repeater, means for completing a second bridge across said first section at the far end thereof to energize said relay, a control circuit for said switch closed 15 by said relay, an inductive winding in said control circuit constituting a bridge of said second section, means for interrupting said second bridge to operate said switch through the medium of said line relay and control 20 circuit to establish a talking connection between a calling and a called line, and means for opening the bridge across the second section and for conductively connecting the conductors of the two sections whereby said control circuit is maintained closed by way of 25 said second bridge.

17. In a telephone system, a trunk line comprising two inductively connected sections the second of which terminates in an 30 automatic switch, a repeater at the junction of said sections, a line relay in bridge of the first section at said repeater, means for completing a second bridge across said first section at the far end thereof to energize 35 said relay, a control circuit for said switch closed by said relay, an inductive winding in said control circuit constituting a bridge of said second section, means for interrupting said second bridge to operate said switch 40 through the medium of said line relay and control circuit to establish a talking connection between a calling and called line, means for automatically opening both the line relay bridge and the bridge across the 45 second section, and means for conductively uniting the conductors of the two sections whereby said control circuit is maintained closed by way of said second bridge.

18. In a telephone system, a trunk line 50 comprising two inductively connected sections, the second section terminating in an automatic switch, a relay in bridge of the first section and energized over the conductors thereof to close a control circuit for 55 said switch, means for operating said switch through the medium of said relay and control circuit to establish a talking circuit between a calling and called line, an inductive winding in said control circuit constituting a bridge of said second section, and automatic means operated over said control 60 circuit for holding said second bridge open during conversation, a section of said control circuit extending over a part of said 65 second section.

19. In a telephone system, a trunk line comprising two inductively connected sections, the second section terminating in an automatic switch, a relay in bridge of the first section and energized over the conductors thereof to close a control circuit for 70 said switch, means for operating said switch through the medium of said relay and control circuit to establish a talking circuit between a calling and called line, an inductive 75 winding in said control circuit constituting a bridge of said second section, and automatic means operated over said control circuit for holding both bridges open during conversation, a section of said control circuit extending over a part of said second section.

20. In a telephone system, means for connecting a calling and a called line including 80 a trunk line comprising two inductively connected sections, a repeater at the junction of said sections, a controlling relay connected in a bridge of one section of the trunk line, and means for conductively uniting the conductors of said sections by way of the windings of said relay.

21. In a telephone system, means for connecting a calling and a called line including 85 a trunk line comprising two inductively connected sections, a repeater at the junction of said sections, a controlling relay connected in a bridge of one section of the trunk line, and means controlled by the subscriber on the called line for conductively uniting 90 the conductors of said sections by way of the windings of said relay during conversation.

22. In a telephone system, means for connecting a calling and a called line including 100 a trunk line comprising two sections, a repeater at the junction of said sections, condensers inductively connecting said sections, a double wound controlling relay connected in a bridge of one section of the trunk line, and means controlled by the subscriber on 105 the called line for conductively uniting the conductors of said sections during conversation by connecting the two windings of said relay in shunt of the said two condensers, respectively.

23. In a telephone system, means for connecting a calling and called line including 110 a trunk line comprising two inductively connected sections, a repeater at the junction of said sections, a controlling relay in said repeater in bridge of the first section, a second relay in said repeater in bridge of the second section, and circuit controlling mechanism for disconnecting one of said 115 relays from the trunk line and for changing the other relay in relation to the said trunk line from bridged to series connection.

Signed by me at St. Paul, Ramsey County, Minnesota, this 7th day of March, 1916.

BERNARD C. GROH.
